UNITED STATES PATENT OFFICE.

FRANKLIN H. FICKETT AND JOHN W. REID, OF CHICAGO, ILLINOIS.

FOLDING OR CABINET BATH-TUB.

SPECIFICATION forming part of Letters Patent No. 281,555, dated July 17, 1883.

Application filed January 15, 1883. (No model.)

To all whom it may concern:

Be it known that we, FRANKLIN H. FICKETT and JOHN W. REID, both of Chicago, in the county of Cook and State of Illinois, have invented certain new and useful Improvements in Folding or Cabinet Bath-Tubs; and we hereby declare the following to be a full, clear, and exact description thereof, which will enable others skilled in the art to which our invention relates to make and use the same, reference being had to the accompanying drawings, forming a part hereof, and in which—

Figure 1 represents a side sectional elevation, showing the bath-tub down, with its hinged base *g* attached. Fig. 2 represents a side sectional elevation with the bath-tub down, showing the interior cupboard or case, *h*, in section. Fig. 3 represents the lower or foot end of the bath-tub, showing the improved trap, and also 20 the attached splashes *p p'*. Fig. 4 represents the weight *j* with one of its parts *j'* detached. Fig. 5 represents a front elevation of Fig. 2, the bath-tub being removed.

Like letters of reference indicate like parts. 25 The nature and object of our invention will fully appear in the following description of the several parts:

In the drawings, *a* represents the bath-tub, hinged at *c*; and *b*, the cabinet into which it 30 folds or closes. To the upper edge of the foot end of the tub are attached pulleys *c'*, and to the rear side of the cabinet or wall, about opposite to the pulleys *c'*, are attached pulleys *c''*, and in the upper end of the weight-chamber 35 *s* are fixed pulleys *c'''*. To the bottom of the rear wall of the cabinet *b* are attached ropes *l* at *t*, each of which passes over the pulleys *c'* *c''* *c'''*, and down on the inner side of the last-mentioned pulleys to a weight, *j*, to the arms 40 of which the ropes *l* are fastened. Said weight *j* is provided with one or more removable weights, *j'*, constructed as shown, so that any desired number of blocks *j'* may be added, so as to properly adjust and balance the resist- 45 ing weight *a*. The weight *j* plays in a shaft, *s*, which serves as a guide to it. The front wall of said shaft forms the rear wall of the case or cabinet *h*. Said case fills the interior portion of the tub *a* when folded up, and is 50 provided with doors *i* and shelves 1 2 3 4, to hold such articles as are used in connection with the bath-tub.

Instead of forming the gas-trap in the box *m*, as in Fickett's former patents, the curved pipe *n* plays through the top and in the 55 box *m*, as formerly, gas-tight; but the box *m* has no other internal mechanism, but discharges directly into the waste-pipe *f*, which is trapped in the usual manner; but to avoid the danger of any gases escaping through the 60 pipe *d*, it is first bent into the form as shown in Fig. 3, and then the curve *e* is bent outward, as shown in Fig. 2, so that when the tub is raised the water will not flow out of the part 65 *e*, nor will it when the tub is down, thus forming a sealed trap in whatever position the tub may be. Thus the overflow-pipe *d* serves the double purpose of an overflow-pipe and a gas-trap.

To keep the tub *a* level with the raised 70 hinges *c* and in proper position, a fixed support, *k*, is attached to it, which also forms a handle by which the tub is drawn down or out for use. Said handles may be made ornamental, and thus add greatly to the beauty 75 and appearance of the apparatus.

In this improved construction the base-board *g* at the foot of the bath-tub, when erected into its cabinet, forms a part of the continuous base-boards around the room, the cabinet being made in a closet or adjoining room. Said base-board extends only across the width of the cabinet, and is so hinged at or near the floor, in any convenient manner, that it may move in and out. The bath-tub and base-board *g* are hitched together by a flat metal strip, *o*, fastened by pivots at each of its ends, on which it works—one attached to the bath-tub, the other to the end of the base-board, as shown in Fig. 1—or hinged thereto in any other 90 convenient manner, and in such radial position to the hinges of the bath-tub and base-board as will permit the bath-tub to rise and fall, and with it, and throw out the base-board into the horizontal position with the tub, so as 95 to permit the tub to come out, as shown in Fig. 1, and in dotted position when the tub is raised, the base-board *g* then forming a part of the base-board of the room. The flat metal strip *o* is preferred, because it can, by a simple pin 100 or round nail, be attached to the end of the board *g*, and thus form a joint; but it is evident that any other form of connection attached so as to form joints at the ends, attached,

respectively, to the tub and base *g*, will answer the purpose equally well.

Splashers attached to the longitudinal side of the tub may be hinged to the lower edge 5 and made to fold upward, as shown at *p*, or attached to the upper edge and folded downward, as shown at *p'*. They extend along the entire length of the tub, and are made of any water-proof material, which may or may not be 10 mounted on a frame, and they empty into a drip-pan of the bath-tub, as shown in Fickett's former patents, when it is raised. The object of the splashers is to catch any water splashed out of the tub in use upon the walls, 15 carpet, &c.

The arrangement and operation of the cords *l* and pulleys *c' c² c³* is such that when the tub is down the weight *j* exerts its greatest force, and as the tub rises the pulley *c'* descends below the pulley *c²* toward the fastening *t*, and thus the same weight gradually loses 20 its force on the tub *a* in about the same proportion as the tub requires less weight as its outer end passes through the various angles 25 of elevation until it is up, and thus a steady, uniform resistance is given with the same weight, which, when properly balanced, requires little or no other force than that to overcome the friction.

What we claim as new, and desire to secure 30 by Letters Patent, is—

1. The tub *a*, hinged at *c*, and provided with the pulleys *c'*, the fixed pulleys *c² c³*, and cords *l*, fixed at *t*, and weight *j*, substantially as specified.

2. The tub *a*, hinged at *c*, and provided with the pulleys *c'*, the fixed pulleys *c² c³*, and cords *l*, fixed at *t*, and weight *j*, provided with removable blocks *j'*, substantially as specified.

3. The tub *a*, hinged at *c*, and base-board *g*, 40 hinged upon the floor, connected by the pivoted strip *o*, as specified.

4. In a bath-tub, *a*, hinged at *c*, and having a discharge-pipe, *n*, the pipe *d*, provided with part *e*, doubly bent, substantially as and for 45 the purpose specified.

5. In a cabinet bath-tub, the folding splashes attached longitudinally to the sides of the tub *a*, below its upper edge, substantially as specified.

FRANKLIN H. FICKETT.
JOHN W. REID.
